UNITED STATES PATENT OFFICE.

HARRY Y. ARMSTRONG, OF SPRINGFIELD, MASSACHUSETTS.

WRAPPING-MACHINE.

1,341,408.

Specification of Letters Patent. Patented May 25, 1920.

Aplication filed August 7, 1918. Serial No. 248,763.

To all whom it may concern:

Be it known that I, HARRY Y. ARMSTRONG, a citizen of the United States, and a resident of Springfield, in the county of Hampden and State of Massachusetts, have invented 5 certain new and useful Improvements in Wrapping-Machines; and I do hereby declare that the following is a full, clear, and exact description thereof, reference being 10 had to the accompanying drawings, and to the characters of reference marked thereon, which form a part of this specification.

This invention relates to improvements in 15 wrapping machines for wrapping or inclosing articles of merchandise such as food-stuffs, tobacco, gum, chocolates, and confections in suitable wrappers, whereby the same is wrapped and sealed to render the packages 20 impervious to poisonous gases, atmospheric conditions, and so forth. The articles to be wrapped may be in the form of cakes, loaves, sticks, and the like, and will hereafter, for 25 brevity, be termed articles. It is known that poisonous gases and other foreign substances will penetrate wrapped articles of merchandise 30 when the wrappers are not properly sealed or the wrapper properly treated or impregnated, and that some classes of merchandise are impaired by contact with tinner foil. It has also been found that deleterious 35 gases and foreign substances such as excess hot sealing material can strike into the material of the articles being wrapped when the wrappers are sealed by the known heat sealing method, wherein a wax paper, such 40 as paraffin impregnated paper, is used as a wrapper and the wrapper is sealed by the application of heat against the flaps, which has 45 the effect to soften the wax or sealing material of the flaps to such an extent as to cause the wax to act, upon subsequent hardening, as the medium to seal the flaps. This 50 is particularly objectionable when the wrappers so sealed lie against the article or lie against the previously sealed seam, and it 55 is to an extent objectionable when the sealed wrapper is the secondary wrapper to overlie a primary wrapper.

One of the objects of the present invention 55 is to fold and seal the overlying flaps or folds of the wrapper in such manner that after the article has been wrapped and the flaps or folds sealed thereover the folds and seams will lay closely on the articles to prevent the passage of poisonous gases through

the sealed joint and prevent the gases striking into the article, and also facilitates the handling of the wrapped package.

Another object of the invention is to provide means to protect the article when being 60 sealed from deleterious gases and excess hot sealing material produced in heating the adhesive medium by which the overlapping folds are sealed, and, therefore, prevent the 65 gases and sealing material striking into the article. The said wrapper may consist of a waxed paper, which in its normal condition is impervious to gases, moisture and other substances, in which event the wax by which 70 the paper is impregnated is relied upon to furnish the adhesive medium to seal the overlapping folds or flaps of the wrapper.

Heretofore it has been a common practice when wrapping merchandise in waxed paper to heat the flaps or folds of the paper to cause 75 the wax to flow sufficiently to produce a reliable adhesive medium by which to cause the folds or flaps to adhere. In this practice it has been found that the gases driven off from the wax paper when so heated and the 80 hot sealing material penetrates the merchandise to such extent as to injure the quality or impair the taste of the merchandise, for the reason that under prior practice the heat to cause the wax to flow is applied to the wrap- 85 per when the overlapping flaps of the wrapper lie directly on the article of merchandise. To overcome this defect in prior practice, it is proposed in accordance with the present invention, to apply between the article and 90 the folds of the wrapper, which are heat sealed upon each other or adhered together, a thin medium which is impervious to gases, such as a thin impervious element, as a plate, said excluding element lying between the article and the wrapper folds or flaps so as 95 to prevent contact of the folds or flaps with the article during the time that heat is applied thereto to cause the wax to flow to produce the desired sealing effect. This means 100 of protecting the articles against the deleterious effect of gases or hot wax driven off from the wax or adhesive medium when heated may be employed in packages where only the side folds or flaps of the wrapper 105 are sealed, or where both the side folds or flaps and the end folds or flaps are sealed.

Another object of the invention is to produce a machine of this character to rapidly wrap the articles, and in this respect the 110

machine embraces means to cause a wrapper strip to continuously pass through the machine, and to receive the articles and to be folded about the article as it travels through the machine and the wrappers to be sealed while moving.

A further object of the invention is to provide a secondary folding mechanism having a run-way across which the side wrapped articles are delivered and by which the end flaps are sealed as they travel therethrough.

Other objects of the invention are to improve and simplify wrapping and sealing machines of the general character described and to produce a machine which is rapid and effective to wrap and seal packages.

The invention consists in the arrangement and construction of the parts as shown in the drawings and described in the specification, and is pointed out in the appended claims.

In the drawings,

Figure 1 is a plan view of a wrapping machine embodying my invention, partly in section,

Fig. 2 is a side elevation thereof.

Figs. 3 and 4 are vertical sections on the lines 3—3 and 4—4, respectively, of Fig. 2. Figs. 5, 6, and 7 are vertical sections on the lines 5—5, 6—6, and 7—7, respectively, of Fig. 1.

Fig. 8 is a vertical section on the line 8—8 of Fig. 2.

Figs. 9, 10, and 11 are perspective views of the article in the course of its wrapping operation.

In the drawings, the supporting frame is principally omitted, except only as necessary to illustrate the relative positions of the different elements of the wrapping mechanism and to indicate the positions of bearings for the various shafts constituting the driving mechanism for the wrapping mechanism. It will be understood that the frame may be of any preferred design most suitable for the purpose.

Preliminary to a detailed description of the elements of the wrapping mechanism, it may be stated that, so far as the wrapping of the article is concerned, in respect of the present embodiment of the invention, the wrappers for the individual articles are produced by drawing a continuous strip of wrapping paper from a reel suitably located on the frame through a run-way or guide and forming the wrapper strip as it travels through the machine into a closed envelop or tube with the side margins of the strip folded toward and lapping one over the other to constitute the envelop or tube, and feeding the articles to the forming tube from a suitable magazine that is located in position to deliver the articles on the traveling wrapper before the tube assumes its com-

plete form; the side margins of said wrapper strip being, by suitable side folding means, folded inwardly together and overlapped over the tops of the articles. If desired, an insert card or sheet may be inserted into the forming tube in rear of the point where the articles are fed on the moving wrapper sheet and at the place where the flaps overlie one on the other and are thereafter sealed. After the side margins of the wrapper sheet have been folded one over the other to complete the tube, the said tube and contained articles are caused to travel beneath a hot plate, with the overlapped folded margins in contact therewith to heat the wax or other suitable adhesive material to cause it to flow to seal the overlapped side margins of the tube together. The tube and contained articles are then caused to pass beneath a presser device which exerts pressure thereon for a time required to allow the wax or adhesive material to set or harden. Means may be provided for causing the wrapper strip and envelop to continuously pass through the folding means and beneath the hot plate and presser means, and the articles are discharged from the magazine onto the traveling wrapper sheet at such intervals as to space them from each other so that the articles in the tube, after passing from the presser means, are separated by unfilled portions of the tube. The tube is thereafter transversely severed between the articles at such unfilled portions, the unfilled portions of the tube at the ends of the individual articles constituting end folds or flaps which may be sealed and folded over the sides of the packages thus formed, if desired. The said severing means is operated in timed relation to the means by which the articles are delivered to the wrapper so as to insure the severing of the unfilled portions of the tube midway between the articles. Therefore, if it be desired to seal and fold the end flaps over the package, the individual packages may be delivered to a second or supplemental folding mechanism which, in the present instance, is disposed at a right angle to the side folding and sealing mechanism, and the end folding mechanism embraces means to cause the end flaps to be folded upwardly over the package and as said packages are passed continuously through the supplemental folding mechanism against the sides thereof. The packages with the end flaps thus folded thereover may be sealed by passage thereof under a second hot plate to cause the wax or adhesive material to flow and the ends of the wrapper may be caused to pass in contact with a second presser device to set the adhesive material.

Just in rear of the position where the articles are discharged onto the traveling wrapper strip may be located a thin plate,

which, in the present instance, is fixed at one end to the machine and extends rearwardly beneath the hot plate and the presser means and is free at its rear end. It is so arranged 5 that the side margins of the wrapper strip are folded inwardly over and in contact with said plate, instead of being brought into contact with the articles themselves. The closed tube with the spaced articles 10 therein are free to pass away from the free end of the plate. Said plate, being located between the overlying side margins of the wrapper and the articles, excludes the passage of gases set up by the heating of the 15 wax or adhesive medium and excess hot sealing material and thereby avoids the contact of said gases and sealing material with the articles.

When the individual packages, formed by 20 severing the tube at the unfilled portions thereof between the articles, are passed through a second folding mechanism to fold and seal the end flaps, the said end flaps may be folded over and against other plates impervious to gases and hot sealing material 25 that lie over the ends of the packages so as to prevent the entrance of gases and sealing material into the packages when the wax or adhesive material of the end flaps is being 30 heated to seal the flaps.

As shown in the drawings, 10 designates as a whole a run-way comprising in part a bottom and laterally spaced sides, through which the wrapper is passed when it is 35 formed into the wrapping tube in which the articles are wrapped. Said run-way may be supported on any suitable frame, not necessary herein to be shown in full detail. In the present machine, the wrapper strip is 40 continuously moved through the run-way and is acted upon to form it in a tube.

The wrapper strip W is drawn from a roll supported on a suitable reel 12 that may be rotatively supported on the frame in any 45 suitable manner at the front end of the run-way 10. The run-way is narrower than the original width of the wrapper strip, and means are provided, as hereinafter described, to fold the side margins of the 50 wrapper strip inwardly toward each other and in overlapping relation to form a closed tube. 13 designates a magazine to contain the articles A. It is provided at its bottom with a guide 13' for the wrapper 55 strip to hold the strip flat while passing beneath the magazine. Said magazine is located over the run-way and is supported in any suitable manner on the machine frame. It is open at its bottom for the passage there- 60 through of an ejector 14 by which the bottom-most articles are transferred onto the moving wrapper strip just before said wrapper strip is formed into a tube. Said ejector is operated from the main driving shaft 15 65 of the machine,—the operating connection

shown comprising a pitman 16 that is loosely connected at one end to a disk 17 fixed to said driving shaft and is loosely connected at its other end at 18 to the outer end of the ejector.

Located in rear of the magazine 13 are folding disks 20, 21, one at each side of the run-way 10. Said folding disks are formed with concave lower faces 22 and one of the disks, the disk 21 as herein shown, lies in a plane above the plane of the disk 20. Said disks are of such diameter that they overlap each other above the plane of the run-way at the central portion thereof. The folding disks are fixed to the upper ends of upright 70 shafts 22, 23, to the lower ends of which are fixed beveled pinions 24 (Fig. 4). Said bevel pinions 24 mesh with other bevel pinions 25 that are fixed to and rotate with a short horizontal shaft 26 arranged transversely beneath the run-way and may be mounted in any suitable bearings on the machine frame. Said shaft 26 is provided at its outer end with a bevel pinion 27 that meshes with a bevel pinion 28 that is fixed 75 to and rotates with a horizontal counter-shaft 29 that is disposed at one side of and below the run-way, and is mounted in bearings 30 carried by suitable brackets on the machine frame, not shown. Said counter-shaft is provided at its front end with a bevel pinion 31 which meshes with a bevel pinion 32 that is fixed to and rotates with the main driving shaft 15.

35 designates a heating chamber located above the run-way and supported in any suitable manner on the machine frame. The lower wall 36 of the heating chamber constitutes a hot plate that is arranged parallel to and above the run-way. The heating chamber may be heated in any suitable manner. It is herein shown as a steam heated chamber and is equipped with a pipe to transmit the steam thereto. 40 designates a presser device that is located in rear of the heating chamber 35, and, as herein shown, is supported on said chamber. The presser device comprises a horizontal body which supports a series of bristles 41 that constitutes the active member of the presser 45 device, the whole having the form of a brush. The lower face of the brush is in the plane of the hot plate 36, and, therefore, is located over and parallel to the run-way and bears directly on the upper side of the tube formed 50 by the wrapper.

The section of the run-way beneath hot plate and presser device is a yielding section 42. It is yieldingly supported on a depressed portion 43 of the frame through the 55 medium of stems 44 attached to and depending from the section 42 and extending through openings in the depressed frame member 43. Spiral springs 45, interposed between the depressed member 43 and said 60

yielding section 42, serve in coöperation with stops on the stems to normally hold the said yielding section in the general plane of the run-way, but permits said section to yield 5 downwardly to accommodate packages of varying thicknesses. The said yielding presser plate has the effect to yieldingly force the packages against the hot plate and the presser device as the packages and the 10 inclosing wrapper tube passes thereunder.

The concave faced folding disks 20, 21 act on the side margins $w-w$ of the wrapper strip to fold said margins inwardly with one of the margins overlapping the other, due 15 to the fact that one of said disks, the disk 21 as herein shown, rotates in a plane above the plane of the other disk 20. The articles A are ejected from the magazine 13 on the wrapper strip W in front of the folding 20 disks and in the forming tube T. In order that the wrapper while passing beneath and rearwardly from the magazine may be held flat so that the articles may be delivered on the wrapper strip when flat, a fan shaped 25 spreader device 50 is arranged over the run-way and over the plane of the wrapper strip between the magazine and folding disks 20 and 21, the pointed end of said spreader device being directed rearwardly toward said 30 folding disks. The engagement of said side margins w, w of the wrapper strip by said rotative concave faced folding disks causes the wrapper to assume the tube form as the wrapper strip passes beneath and between 35 said folding disks.

If the wrapper strip be a waxed paper, the wax material by which the paper is impregnated is relied upon to seal the tube at the overlapping margins of the wrapper, 40 the said wax material being heated by contact with the hot plate 36 as the wrapper and the inclosed articles pass thereunder, with said overlapping margins of the wrapper in contact with the hot plate to cause the wax 45 of the wrapper margins of flaps to soften. The wrapper strip and the tube formed therefrom are moved through the run-way and after the overlapping margins of the tube pass rearwardly away from and out of 50 contact with the hot plate, said margins are brought into contact with the yielding presser device. The effect of the presser device is to hold the overlapping margins of the wrapper tube in contact with each other 55 while the wax material of the paper sets or hardens, so that when the tube moves rearwardly from under the presser device the overlapping margins of the wrapper tube are reliably adhered together. The yielding 60 section 42 that is spring held up against the wrapper tube and inclosed packages insures good contact of the overlapping margins of the wrapper tube with the hot plate and the presser device as the tube passes 65 thereunder.

The tube T and the articles inclosed therein are caused to move rearwardly through the run-way and to effect a drawing action on the wrapper strip to unwind the strip from the reel 12 through the medium of 70 horizontal rotating rollers 53, 54 that are arranged in opposing pairs at the opposite sides of the run-way and are adapted for contact with the sides of the tube and contained packages. The feed rollers 53 are 75 herein shown as formed integral with or attached to the rotating folding disks 21, 22. The other feed rollers 54 are fixed to the upper ends of vertical shafts 55 that may be mounted in suitably formed bearings on the 80 machine frame. To the lower ends of said shafts are fixed bevel pinions 56 which mesh with bevel pinions that are carried by short horizontal shafts 57 below and extending transversely across the run-way. Said shafts 85 57 carry at their outer ends bevel pinions 58 that mesh with a series of bevel pinions 59 which are fixed to and rotate with the countershaft 29 above referred to. The faces of the feed rollers 53, 54 may be composed of a surrounding resilient, preferably roughened, cover, so as to cause the rollers to reliably engage the tube and contained packages and thereby to positively feed the tube through the run-way without slippage 90 and to positively draw the wrapper strip off the reel 12.

The mechanism for operating the ejector 14 is so timed, relatively to the speed of travel of the tube and the wrapper strip, as 100 to deliver the articles on the wrapper strip, at predetermined distances apart, as indicated in Fig. 1, so that when the articles are delivered to the wrapper and the wrapping tube formed therefrom, there remains between adjacent articles inclosed in the tube unfilled sections w^2 of the tube. These unfilled sections w^2 are of such length that when they are transversely severed, mid-way 105 between the articles contained in the tube to 110 produce the individual wrapper packages, the wrappers of each side folded package are formed with endwise extending end flaps w^3 (Figs. 10 and 11) which may or may not be folded over the side of the package and 115 sealed, depending upon the article wrapped therein.

The means herein shown for transversely severing the tube at the unfilled sections w^2 are made as follows:

60 (Figs. 1 and 2) designates a rotating block which is arranged transversely across and over the run-way 10 near the junction thereof with the run-way 11 at the rear end of and disposed at a right angle to the run-way 10. Said block is provided with diametrically opposed cutting knives 61 that extend slightly beyond the opposite side edges of the block. 62 designates a coöperating block arranged below and is trans- 125 130

versely across the run-way and provided at its opposite side edges with grooves 63 adapted to register with and receive the knives when said knives are brought to their cutting positions. The block 60 is provided at the side of the knives 61 with yielding presser members 64 which are seated in grooves in the blocks and are backed by springs 65. Said springs normally hold the presser members projected beyond the edge faces of the blocks. When the upper and lower blocks are brought into operative cutting positions, with one of the knives 61 registering with one of the grooves 63, said presser members, by contact with the opposing edge face of the lower block, are forced backwardly into their grooves against the action of their backing springs. The presser members 64 serve as means to hold or press the unfilled tube sections against the lower block 62 and thus hold the sections w^2 taut across the grooves 63 when the knives 61 are brought into cutting relation to said sections to sever the tubes. The blocks 60, 62 also constitute drawing rolls when they are peripherally in contact to assist in drawing the tube through the machine.

The upper and lower cutting blocks are fixed to and rotate with upper and lower shafts 66, 67, respectively, arranged transversely of the runway 10 and mounted in suitable bearings 68 on the machine frame. The shafts 66, 67 are provided at their ends remote from the cutting blocks with meshing toothed gears 68', 69 (Fig. 6) and the lower shaft 67 is provided at its end remote from its toothed gear 69 with a bevel pinion 70. Said bevel pinion meshes with a bevel pinion 71 (Figs. 1 and 2) that is fixed to a short horizontal shaft 72 which is disposed transversely to and below the supplemental runway 11 and is mounted in suitable bearings 73, 73 on the machine frame. The shaft 72 is provided at its end remote from the pinion 71 with a toothed gear 75 that meshes with a toothed gear 76 that is fixed to and rotates with the counter-shaft 29, said counter shaft being extended transversely below the receiving end of the supplemental run-way.

With the driving construction described, it will be noted that the cutting device blocks 60, 62 are rotated at equal speeds so as to bring the diametrically opposed cutting knives of the block 60 and grooves 63 of the block 62 into register. It will be furthermore observed, by reason of the fact that the said cutting device shafts are driven from the counter-shaft 29, which is in turn operatively connected to and driven from the main driving shaft 15 that operates the ejector 14, and the further fact that the shafts of the feed rollers 53 and 54 are driven from said counter shaft 29, said cut-

ting knives are operated in timed relation to the ejector by which the articles are delivered to the wrapper, and to the feed rolls 53, 54. Therefore, the unfilled sections of the tube are accurately presented to the cutting knives as the tube travels through the run-way to insure that the unfilled sections of the tube will be severed at their longitudinal centers to produce equal length end flaps on the side wrapped packages. 70

Referring now to the thin plate that is adapted to be interposed between the articles in the formed tube and the overlapping margins of the wrapper sheet forming the tube, for the purpose set forth, the arrangement and mounting of said plate is made as follows:

80 designates an elongated flat metal plate of a width somewhat less than that of the articles being wrapped. The thickness of 85 said plate is enlarged in the drawings in order to clearly show the same (Fig. 4). It will be understood, however, that said plate will be made quite thin so as to occupy but little space in the formed tube above the articles to thereby allow the tube to be wrapped closely about the articles and to avoid slackness of the wrapper when the package is advanced away from the plate or excluding element. The front end of 95 the plate is fastened to the machine frame, and, as herein shown, the extreme front end 81 of said plate is curved upwardly away from the run-way just in rear of the magazine 13. The main portion of the plate lies 100 horizontally over the run-way and is vertically spaced a distance therefrom equal to the thickness of the articles being wrapped, and is of substantially uniform thickness in its part that lies parallel to the runway and 105 is flat on its upper and lower sides for presentation to the articles and wrapper flaps or margins. The excluding element does not, therefore, deform the articles and permits the wrapper to be wrapped closely 110 about a relatively rigid or non-deformable article. Said plate extends between the folding disks 20, 21 and beneath the hot plate 36 and presser device therebeyond, and terminates at the rear end of the presser 115 device. The plate is free or unconnected to the machine at its rear end so that the traveling wrapper tube may pass freely therefrom. Said plate 80 also lies beneath the spreader block 50 so that it projects into 120 the forming tube at the point of the tube where the side margins are folded upwardly, but before said margins have been folded inwardly by said folding disks 20, 21. The presence of the plate between the 125 articles and the overlapping margins of the tube provides a sealing support against which the wrapper flaps are pressed when being heated by the plate 36 and also when said wrapper flaps are pressed upon by the 130

presser device 40, and said plate also prevents access of gases and heated wax set up by heating the wax material or adhesive medium of the wrapper flaps from coming in contact with and striking into the articles in a way to injure the same.

Provisions are herein shown for placing insert sheets S, containing advertising matter or the like, in the forming tube just before the tube takes final form. The insert answers a two-fold purpose,—as an advertising medium, and also as means, either separately or in conjunction with the plate 80 to keep the heat from the articles being wrapped and prevent foreign gases and heated wax striking into the articles and thus acts as an additional wrapper at this point. The means herein shown for placing the insert sheets in the forming tube are made as follows:

83 designates a magazine in which the insert sheets S are placed. Said magazine is arranged just in rear of the magazine 30 a distance above the run-way. Between the magazine 83 and the run-way is located a rotative stripper roll 84, the periphery of which is partially covered with a friction cover 85, of rubber or the like which acts on the sheets S to strip the lowermost sheet from the bundle of sheets in the magazine 83. The said sheets are guided onto the articles after the latter have been released from the magazine by the stripper through a guide formed between the curved upturned front end 81 of the plate 80 and a guide member 85' arranged in rear of the magazine 13. The stripper roller is fixed to and rotates with a shaft 86, on one end of which is fixed a sprocket wheel 87. Said sprocket wheel is driven from a sprocket wheel 88 on the drive shaft 15 through the medium of a sprocket belt 89. The said stripper roller 84 and the ejector 14 are so timed that an insert sheet S is delivered onto each article after it is transferred from the magazine 13.

The insert sheets are of such width that they are caused to bend or buckle in the forming tube so as to insure proper feeding and placing of the sheets in the forming tube, as shown in Fig. 4.

The supplemental run-way 11, disposed at a right angle to the main run-way 10, embraces in its construction parallel longitudinal angle bars 118, 118 that may be supported on a frame of any suitable construction. Said supplemental guideway 11 embraces at its front end a plate 93 onto which the side wrapped packages are delivered. The main guideway 10 terminates in a plate 94 at its rear end (Fig. 2), which is provided with laterally spaced bridge fingers 95, 95 (Figs. 2 and 8) that are so disposed as to extend through slots 96, 96 in the rotative cutter block 62. Said fingers 95 constitute bridge members between the

plate 94 and the plate 93 of the supplemental run-way when the cutter blocks are out of line with respect to each other over which the packages are delivered to the supplemental run-way. The upper faces of 70 said fingers 95 are in the plane of the plate 93 of the supplemental run-way and below the knives 61 when the latter are in their cutting positions.

The side wrapped packages, with their 75 extended end flaps, are carried rearwardly through the supplemental run-way 11 by means of lugs 98 which are attached to and extend outwardly from endless sprocket chains 99 trained about front and rear 80 sprocket pulleys 100, 101, the forward one of which is fixed to the shaft 72 before referred to and the rear one of which is fixed to a shaft 102 that may be rotatively mounted in bearings supported in any suitable 85 manner on the frame of the supplemental run-way. The said side wrapped packages, with their extended end flaps, are positioned on the run-way 11 by a limiting stop 104 (Figs. 1 and 2) that extends upwardly 90 from the guideway at its outer side, the packages being pushed rearwardly by the block or rolls 60, 62 after each package is severed from the tube.

The end flaps w³ of the packages may be 95 folded upwardly and inwardly toward the upper sides of the packages by parallel folding plates suitably supported on the supplemental run-way frame. Said folding plate comprises front outwardly turned 10 horizontal portions 105, spiral portions 106 beyond the same, and inturned portions 107 lying beyond the spiral portions. The said end flaps, as they are carried rearwardly through the supplemental run-way, are, by 10 contact with said folding plates, turned upwardly and inwardly so as to bring them to the positions shown in Figs. 6 and 7.

Arranged in rear of the end flap folding plates are elongated heating boxes 110 disposed one over each of the guide bars 118, and the bottom walls of which constitute hot plates 111 (Figs. 1 and 5). The end flaps of the packages are caused to bear against the under faces of the hot plates as the packages pass thereunder so as to heat the sealing medium of the layers of the flaps and to cause it to flow to seal said layers of the flaps upon each other and to thereby close the ends of the packages. Said heating 11 boxes may be heated in any suitable manner, as by steam or electricity, and as herein shown are equipped to be heated by gas.

Disposed in rear of the hot plates are presser devices 112, preferably made like the 12 brush presser device shown in connection with the tube sealing mechanism, and against the lower brush faces of which the inwardly folded end flaps pass so as to set or harden the sealing or pasting medium. 13

Said presser devices 112 are arranged in prolongation of the heating boxes 110 and are laterally spaced so as to lie over the in-turned end flaps w^3 of the packages.

5 115, 115 designate thin metal plates (Figs. 6 and 7), which lie beneath the hot plates 111 and the presser devices 112 and between them and the side wrapped articles and extend at their rear ends beyond the 10 rear ends of the presser devices. Said plates may be fastened at their forward ends in any suitable manner to the supplemental run-way frame, as by the webs 116 (Figs. 1, 5, and 6), and the plates are free or un- 15 attached at their rear ends in the same manner as the plate 80 of the tube sealing mechanism is free, and are raised slightly above the packages. Said plates 115 are triangular in cross section, with their thinner edges 20 directed outwardly. The plates extend at their forward ends beneath the spirally formed and inturned portions 106, 107, respectively, of the folding plates, so that as the end flaps of the wrappers are folded 25 upwardly and inwardly they are folded over the outer or thinner margins of the plates 115. The plates, therefore, lie between said folded end flaps w^3 of the wrappers and the sides of the packages when said flaps are 30 passed rearwardly beneath the hot plates 111 and the flexible presser devices 112, so as to hold the end flaps diagonally over and spaced from the upper sides of the packages to thereby seal the layers or members 35 of the end flaps to close the package ends, and without heating the previously sealed side seams.

The supplemental guideway includes in its construction, at the sides of the hot plates 40 and presser devices, the flanged guide members 118, by which the completely wrapped packages are guided as they pass beneath the hot plates and presser devices and are discharged from the machine. The plates 45 115 act to prevent heated gases generated by the heating of the wax and excess heated wax of the wrappers finding its way for contact with the articles wrapped in the wrappers. The plates 115 prevent the end flap heat sealers from heating and opening up the previously sealed side seams.

After the wrapped packages pass the rear ends of the presser devices they are carried rearwardly by the lugs or projections 55 98 of the sprocket chains 99 and are discharged from said traveling chains at the rear end of the supplemental run-way. The packages are now completely wrapped and side and end sealed and ready for further 60 or secondary packing if necessary.

As before stated, the wrapping of the packages and the sealing thereof, if desired, may be completed in the main runway and the end flaps folded over the packages as 65 they are packed for shipping. With some

articles of merchandise, however, it is necessary and desirable to paste the end flaps of the wrappers on the packages.

If desired, the end flaps or folds may be sealed in their extended positions, as shown 70 in Fig. 10, without first folding them toward the sides of the packages. The package shown in Fig. 11, however, may be more compactly stacked than that shown in Fig. 10. 75

It will be understood that the structural details of the machine herein shown more or less diagrammatically, may be considerably varied within the spirit and scope of the invention and that the invention is not 80 limited to the structural details shown, except as to claims wherein the details are specifically set forth, and as imposed by the prior art. For instance, for some products the articles may be differently introduced to the forming tube and the location of the marginal or side flaps of the wrapper correspondingly changed. Moreover, the end flaps may be differently folded, so far as is concerned the excluding element 80 90 without departure from the principles of the invention and without sacrificing the advantages of said excluding element.

The mechanism illustrated for folding the wrapper about the articles and for introducing the inserts into the packages is not herein claimed but is made the subject matter of a divisional application filed on the 13th day of October 1919, Serial No. 330,400. 95

I claim as my invention, 100

1. A machine for wrapping and sealing articles in wax impregnated wrappers comprising means to fold a wrapper about the article to form a folding flap, heat means adapted for contact with said flap to soften 105 the wax thereof, and a thin gas and wax excluding element having non-deforming faces and adapted to lie between said article and said flap when the heat sealing medium acts on said flap. 110

2. A machine for wrapping and sealing articles in wax impregnated wrappers comprising means to fold a wrapper about the article to form a folding flap, heat means adapted for contact with said flap to soften 115 the wax thereof, and a gas and wax excluding element adapted to lie between said article and said flap and having flat faces for presentation toward the article and flap when the heat sealing means acts on said flap. 120

3. A machine for wrapping and heat sealing articles comprising means to fold a wrapper about the article and to form overlapping flaps adapted to lie against the 125 article, heat sealing means adapted for contact with said overlapping flaps to soften the wax thereof, and means whereby a thin gas and wax excluding element having flat, non-deforming faces for presentation to 130

said flaps and article is adapted to be positioned between said article and said flaps when said heat sealing means acts on said flaps.

5. A machine for wrapping and sealing articles in wax impregnated wrappers comprising means to fold a wrapper about the article and to form flaps lying one on the other against said article, heat sealing 10 means adapted for contact with said overlying flaps to soften the wax thereat, and a thin gas and wax excluding element adapted to lie between said article and said flaps and having flat faces for presentation to the article and flaps when the heat sealing 15 means act on said flaps.

6. A machine for wrapping and sealing articles in wax impregnated wrappers comprising means to fold a wrapper about the 20 article and to form overlapping flaps against said article, heat sealing means adapted for contact with said flaps to soften the wax thereof, and a thin gas and wax 25 excluding element abreast said heat sealing means of substantially uniform thickness throughout and adapted to lie between said article and said overlying flaps.

7. A machine for wrapping and sealing articles in wax impregnated wrappers comprising means to fold a wrapper about the 30 article to form a folding flap, heat sealing means for contact with said flap to soften the wax thereof, a thin gas and wax excluding element abreast said heat sealing means 35 adapted to lie between said article and said flap and having non-deforming faces for presentation to the article and said flap, and presser means abreast of and fixed relatively to said excluding element and adapted 40 to bear upon said flap while the wax sets or hardens.

8. A machine for wrapping and sealing articles in wax impregnated wrappers comprising means to fold the side margins of 45 the wrapper upon the article and in overlying relation to each other, a thin gas and wax excluding plate adapted to lie between said article and said overlying wrapper margins and having flat, non-deforming 50 faces for presentation to said article and said margins, and means to apply heat to said overlying margins and to press said margins against said plate.

9. A machine for wrapping and sealing articles in wax impregnated wrappers comprising means to fold a wrapper about the article to form a folding flap, heat sealing means adapted for contact with said flap to soften the wax thereof, means associated with the folding means to cause the wrapper and article to travel past said heat means, and a thin, elongated, free-ended gas and wax excluding element abreast said heat 60 means having non-deforming faces for presentation toward said article and flap and

adapted to lie between said article and flap when the latter is in contact with the heat means, the wrapped article being movable when the flap is sealed away from the free end of said excluding element.

10. A machine for wrapping and sealing articles in wax impregnated wrappers comprising means to fold the side margins of a wrapper in overlying relation against the article, heat means to soften the wax at said 75 margins, means associated with the folding means to cause the wrapper and article to travel past and with said margins in contact with said heat means, and a thin, elongated, free-ended gas and hot wax excluding element 80 abreast said heat means and of substantially uniform transverse thickness and adapted to lie between said article and overlying margins, the wrapped article being movable, when sealed, away from the free 85 end of said plate.

11. A machine for wrapping and sealing articles in wax impregnated wrappers comprising means to fold the side margins of a wrapper in overlying relation against the 90 article, heat means to soften the wax at said margins, means associated with the folding means to cause the wrapper and article to travel past and with said margins in contact with said heat means, a thin, elongated, 95 free-ended gas and hot wax excluding element abreast said heat means and of substantially uniform transverse thickness and adapted to lie between said article and overlying margins, and presser means abreast 100 said excluding element to engage the sealed margins of the wrapper to fix or harden the wax at said margins.

12. A machine for wrapping and sealing articles in wax impregnated wrappers comprising means to side fold the wrapper to produce overlying flaps that lie against the article and end flap beyond the article, heat means to soften the wax at said flaps, means associated with the folding means to cause 105 the wrapper and article to travel past and with said flaps in contact with said heat means, a gas and wax excluding element abreast said heat means adapted to lie between said article and said flaps, means to 110 turn said end flaps toward the side wrapped package, means to seal the end flaps, and means to space the end flaps from the first sealed flaps while the end flaps are being sealed.

13. A machine for wrapping and sealing articles in wrappers impregnated with a fusible sealing substance comprising a preliminary and a secondary runway arranged at an angle to each other, means to feed 115 articles on a wrapper, means to cause said wrapper and articles to be fed through the primary runway, means at the primary runway for folding the side margins of the wrapper in overlying relation against the 120

- articles, heat means against which the overlying wrapper margins travel to soften the sealing substance thereat, an elongated gas and wax excluding element disposed parallel to the primary runway and adapted to lie between the articles and said overlying margins, means to cause the side wrapped article to travel through said secondary runway, folding means to fold the end flaps of the wrapper toward the side wrapped packages, heat means to seal the end flaps, and means to space the end flaps from the wrapper during the sealing of said end flaps.
13. A machine for wrapping and sealing articles in wrappers impregnated with a fusible sealing substance comprising a preliminary and a secondary runway, means at the primary runway for folding the side margins of the wrappers in overlying relation against the articles, fixed heat means against which the overlying wrapper margins travel to soften the sealing substance thereat, an elongated gas and wax excluding element disposed parallel to the primary runway and adapted to lie between the articles and said overlying margins, means to cause the side wrapped article to travel through said secondary runway, folding means to fold end flaps of the wrapper toward the side wrapped packages, heat means to seal the end flaps, and fixed elongated triangular elements above and parallel to said secondary runway adapted to lie between the side wrapped packages and said end flaps.
14. In a hot sealing wrapping machine, means to form a movable wrapper strip into a tube, with the side margins overlapping, means to place the articles into the forming tube, a hot sealing plate against which the tube, with the articles therein, are passed, with the overlapping margins pressed against said hot plate, a wax and gas excluding element adapted to lie between the article and said overlapping wrapper margins when the tube passes against said hot sealing plate, means to fold the end flaps of the wrapper toward the sides of the packages, heat means against which the end flaps are passed, and wax and gas excluding elements adapted to lie between said end flaps and packages while said flaps are passing against the latter heat means.
15. In a hot sealing wrapping machine, means to form a movable wrapper strip into a tube, with the side margins overlapping, means to place the articles into the forming tube, a hot sealing plate against which the tube, with the articles therein, are passed, with the overlapping margins pressed against said hot plate, a wax and gas excluding element adapted to lie between the article and said overlapping wrapper margins when the tube passes against said hot sealing plate, means to fold the end flaps of the wrapper toward the sides of the packages, heat means against which the end flaps are passed, and wax and gas excluding element disposed parallel to the primary runway and adapted to lie between the articles and said overlying margins, means to cause the side wrapped article to travel through said secondary runway, folding means to fold the end flaps of the wrapper toward each other in overlapping relation against the articles, a hot plate against which the overlapping margins of the wrapper passes, fixed presser means beyond said hot plate against which the sealed margins of the wrapper travels, and means beyond the presser means to transversely sever the wrapper between the articles wrapped therein.
16. A wrapping machine comprising a runway, means to cause a wrapper strip to travel through the runway, means to intermittently deliver articles to the traveling wrapper strip, means to cause the side margins of the wrapper strip to be folded inwardly toward each other in overlapping relation against the articles, a hot plate against which the overlapping margins of the wrapper passes, fixed presser means beyond said hot plate against which the sealed margins of the wrapper travels, and means beyond the presser means to transversely sever the wrapper between the articles wrapped therein.
17. A wrapping machine comprising a runway, means to cause a wrapper strip to travel through the runway, combined with means to fold the side margins of the wrapper strip inwardly against the articles in overlapping relation to each other to form a tube, means to intermittently feed the articles at spaced intervals in the forming tube, means to seal the overlapping margins of the wrapper, means to sever the wrapper between the articles wrapped therein, a second runway disposed at an angle to the first runway, across which the wrapped articles are delivered, means to cause the wrapped articles to travel through the second runway, folding means to fold the end flaps of the wrapper toward the sides of the packages, sealing means to seal the end flaps, and gas and wax excluding means adapted to lie between said end flaps and the sides of the packages during the latter sealing operation.
18. In a wrapping machine, the combination with a runway, means to deliver wrapped packages thereto with the end flaps of the wrappers extending therefrom, means to cause said wrapped packages to travel through said runway, folding means at the sides of the runway to fold said end flaps toward the sides of the packages, hot sealing means to seal said flaps, and fixed free-ended gas and wax excluding plates adapted to lie between said flaps and the packages during the sealing operation.
19. A wrapping machine comprising a runway, means to cause a wrapper strip to travel through the runway, combined with means to fold the side margins of the wrapper toward each other in overlapping relation to form a tube, means to feed the articles to the traveling wrapper strip, a hot plate against which the tube is passed

to seal the overlapping margins of the tube, a fixed, thin, elongated gas and wax excluding element parallel to the runway, adapted to lie between said articles and said overlapping margins abreast the hot plate and having flat faces for presentation toward said articles and said margins, said runway being formed with a yielding section to press

the tube against the hot plate, and means to thereafter transversely sever the tube between the wrapped articles.

In testimony whereof I claim the foregoing as my invention, I hereunto append my signature at Springfield, Massachusetts, this 17th day of July, 1918.

HARRY Y. ARMSTRONG.
